UNITED STATES PATENT OFFICE

156,106

DESIGN FOR A CINCH

Arthur F. Holly, Forsyth, Mont.

Application May 10, 1949, Serial No. 2,555

Term of patent 14 years

(Cl. D38—7)

To all whom it may concern:

Be it known that I, Arthur F. Holly, a citizen of the United States, residing at Forsyth, in the county of Rosebud and State of Montana, have invented a new, original, and ornamental Design for a Cinch, of which the following is a specification, reference being had to the accompanying drawing, forming part thereof.

Figure 1 is a bottom plan view of a cinch showing my new design;

Figure 2 is an edge view thereof; and

Figure 3 is a top plan view of the same.

I claim:

The ornamental design for a cinch, as shown.
ARTHUR F. HOLLY.
